COMBINED HOT-COLD DRINK AND SNACK MACHINE

David M. Adams, 2053 English Road Village
Huntsville, Ala.

Filed Nov. 21, 1968, Ser. No. 14,577

Term of patent 14 years

Int. Cl. D15—12

U.S. Cl. D94—3

FIG. 1

FIG. 2

FIG. 3

FIG. 4

FIG. 5

FIG. 6

FIG. 7

FIG. 1 is a front perspective view of a combined hot-cold drink and snack machine, showing my new design;

FIG. 2 is a perspective view from the front and to the left of the machine to the scale of FIG. 1;

FIG. 3 is a perspective view from the front and to the right of the machine to the scale of FIG. 1;

FIG. 4 is a rear perspective view of the machine to the scale of FIG. 1;

FIG. 5 is an enlarged plan view of the machine shown in FIG. 1;

FIG. 6 is a front elevation view of the machine to the scale of FIG. 5; and

FIG. 7 is a side elevation view of the machine to the scale of FIG. 5.

I claim:

The ornamental design for a combined hot-cold drink and snack machine, substantially as shown and described.
